(57) **CLAIM**

The ornamental design for a smart card reader, as shown and described.

DESCRIPTION

FIG. 1 is a top view of a smart card reader of our new design; FIG. 2 is a bottom view of a smart card reader of our new design;

FIG. 3 is a side view of a smart card reader of our new design;

FIG. 4 is an isometric view of a smart card reader of our new design;

FIG. 5 is a front view of a smart card reader of our new design; and,

FIG. 6 is a rear view of a smart card reader of our new design.

The broken line showing of portions of the smart card reader is included for the purpose of illustrating unclaimed subject matter and forms no part of the claimed design.
